UNITED STATES PATENT OFFICE

JOSEPH FRANCIS HANRAHAN, OF OTTAWA, ONTARIO, CANADA.

REFRIGERATOR-BUILDING.

SPECIFICATION forming part of Letters Patent No. 328,483, dated October 20, 1885.

Application filed August 28, 1885. Serial No. 175,536. (No model.)

To all whom it may concern:

Be it known that I, JOSEPH FRANCIS HANRAHAN, of Ottawa, in the county of Carleton and Province of Ontario, Canada, have invented certain new and useful Improvements in Refrigerators and Refrigerator-Buildings, of which the following is a specification.

My invention relates to refrigerators and refrigerator-buildings, and is designed as an improvement upon the construction set forth in Letters Patent of the United States, granted to me on the 21st day of July, 1885, and numbered 322,446.

The object of the present improvement is to insure a thorough circulation of air throughout every portion of the cooling-chamber, in order to insure the carrying off of all foul or dead air, gases, &c.

In all particulars except those hereinafter specified, the construction remains the same as in my former Patent No. 322,446, to which reference is hereby made for any details or explanations not found herein.

In the annexed drawings, Figure 1 is a horizontal section on the line *w w* of Fig. 2; Fig. 2, a vertical longitudinal section on the line *x x* of Fig. 1; Fig. 3, a vertical transverse section on the line *y y* of Fig. 2; Fig. 4, a vertical cross-section on the line *z z* of Fig. 2.

30 A indicates the ice-chamber, in which a large body of ice is to be stored to cool the air which enters through the ventilator *D* and pipe *E*, and passes through flues *g* and *d* to the cooling or storing chamber *B*, as in my former patent. Additional flues, *g'*, extending along the sides of chamber *A* and opening into chamber *B*, are represented in Figs. 1 and 3 of the drawings closed at top; but these may be used or omitted, as preferred.

40 From the store room or chamber *B* the air passes through an outlet-flue, *C*, to the space above the ice in the chamber *A*, and thence out to the atmosphere through pipe *F* and ventilator *D*, somewhat as before.

45 It has been found in practice that if the outlet opening or mouth of flue *C* be located at or near the center of the ceiling of chamber *B*, as heretofore, the air, taking naturally the shortest course, passes from the flues *d* upward to the center of the ceiling and out through flue *C*, leaving the air in the corners and angles of the room practically undisturbed. As a con-

sequence, the gases, heated air, and vapors given off by meat or other substances stored in room *B* are apt to lodge in the angles and corners, and thus impair the efficiency of the refrigerator. My present invention is designed to obviate this difficulty by causing the air to traverse every part of chamber *B* and to take up and carry off all impure air, gases, and vapors. This object I attain by providing an outlet, *o*, at the corner or angle formed by the meeting of the ceiling of chamber *B* with the wall of chamber *A*, as shown in Fig. 2, said outlet extending along said line from 65 one side of room *B* to the other and opening into flue *C*, in order to give the foul air an equal chance to rise at every point. I also further provide immediately beneath said ceiling a flue or passage, *p*, having a mouth or inlet-opening, *q*, along the side farthest from the outlet *o*, and like said opening, extending from wall to wall of chamber *B*. The flue *p*, which opens directly into the outlet-opening *o*, delivers the air, which enters it through the 75 opening *q*, into the opening *o*, whence it escapes through flue *C* and pipe or outlet *F* to the outside atmosphere. From the opening *o* the flue *C* inclines upward in the direction shown in Fig. 2, or away from chamber *B*, 80 thereby facilitating the entrance of air from flue *p* into said flue *C*, and making the passage equally direct for air from below the ceiling and for air passing through the flue *p*. In passing vertically upward to the outlet *o* and 85 across the end of flue *p* the air produces a suction in said flue and induces a current of air through it, or strengthens the current caused by the varying temperature of the air.

To permit the air-currents to be closely controlled, I provide the valves *h h* at the mouths of the flues *d d*, and also valves *r s*, and *t* in the downflue *E* and upflues *C* and *F*, respectively, the valves *s* and *t* being provided with operating-cords *u*, extending down into 95 chamber *B*, as shown in Fig. 2.

The building being thus constructed, ice is placed in the chamber *A*, and meat or provisions to be refrigerated or preserved are placed in chamber *B*, and the action is as follows: 100 The air of the chamber *A* becomes cooled and consequently heavier, falls to the bottom of said chamber through the flues *g*, passes along the flues *d* into chamber *B*, and passes natur-

ally along the floor to the farther side of said chamber, gradually taking up the heat of chamber B, and rising by reason of the increase of temperature. As soon as the air thus leaves 5 chamber A and enters chamber B, a fresh supply enters chamber A through flue E, and the lighter or more rarefied air from chamber B, being at the top of said chamber, is crowded out by the incoming cold air entering at the 10 bottom. This action produces a current of air from the inlet-pipe E through the ice-chamber A and store-room B to flue C, and thence back to the outer atmosphere through pipe or flue F, in the direction indicated by 15 arrows in Fig. 2. Owing to the greater directness of travel from the point where the cold air enters chamber B to the outlet o, a certain amount of the air will pass directly upward along the wall separating chambers A and B, 20 taking up the heated or vitiated air in that part of the chamber B, while a very large percentage will pass entirely across the chamber B, rise, and flow to outlet o, partly through flue p and partly beneath said flue, thus reaching 25 every part of chamber B, and making it impossible for foul or heated air to lodge at any point. In this way, and by reason of the perfect circulation of the air, the action of the apparatus is materially improved, and perishable articles can be kept with ease and for a 30 long time.

Experience and practical tests have demonstrated the fact that the removal of foul air and gases promptly and thoroughly is quite 35 as essential to the preservation of meats, fruits, and like perishable matters as is the attainment of a low temperature, and by my present plan I accomplish both results in a most efficient and thorough manner.

40 It is not essential that the flue C passes into or through chamber A. If desired, it may

open directly out from chamber B to the atmosphere.

Having thus described my invention, what I claim is—

1. In combination with an ice-chamber, a cooling or storing room, a cold-air inlet from the ice-chamber into the storage-room at or near the floor, an outlet-opening at or near the ceiling of the storage-room, at the side 50 next the ice-chamber, and a flue or passage just beneath the ceiling opening into the outlet, and having an inlet at the side of the storage-room opposite to that at which the cold air enters.

2. The combination of ice-chamber A and storage-room B, communicating at or near the floor-line, an air-inlet for chamber A, outlet o from chamber B, and flue or passage p, having mouth or inlet q and communicating with 60 outlet o, substantially as shown and described.

3. The combination of ice-chamber A, provided with inlet E, and with flues g and d, and storage-chamber B, having outlet o, in communication with the outer atmosphere, and 65 flue p, having mouth or inlet q and communicating with outlet o.

4. In combination with ice-chamber A, storage-room B, communicating therewith at or near the floor, and outlet o, extending entirely across the room B, whereby the accumulation of foul air in the corners is prevented.

5. In combination with chamber A, having inlet-pipe E and flues g and d, storage-room B, having outlet o, and flue p communicating with 75 said outlet, flue C, and pipe or outlet F, and valves r s t, located in the flues E, C, and F, respectively.

JOSEPH FRANCIS HANRAHAN.
